UNITED STATES PATENT OFFICE.

SANFORD S. VAUGHAN, OF OAK PARK, ILLINOIS.

CARPENTER'S PLANE.

Application filed December 19, 1921. Serial No. 523,255.

To all whom it may concern:

Be it known that I, SANFORD S. VAUGHAN, a citizen of the United States, residing at Oak Park, in the county of Cook and State 5 of Illinois, have invented certain new and useful Improvements in Carpenters' Planes, of which the following is a specification.

The present improvements relate more specifically to the means for fastening the 10 cutting blade, bit or iron of a carpenter's hand plane in its operative position, and the chief object is to provide means for holding the cutting element securely while avoiding various objections present in older 15 forms of such planes.

In the accompanying drawings, which form a part of this specification, Figure 1 is a top plan of a hand plane having these 20 improvements applied thereto; and Fig. 2 is a medial longitudinal section through the plane of Fig. 1.

It is common in the art to provide a plane of the general character of the one illustrated, comprising a body or stock, a blade 25 or iron set diagonally with respect to the sole, and clamping means including a screw for holding the blade in its operative position.

The bit or iron 4 is shown as of the 30 double-bit type having in addition to the cutting blade 4 the overlying breaker 5 held adjustably on the iron 4 by the screw 6 movable in the slot 7. Such double irons as well as the single irons are well known in 35 the art, and, since the present improvements apply equally to the double or single blade or iron the reference to such a part in the appended claims are to be understood as applying to either thereof.

The bit 4 rests against a forwardly-and-rearwardly-adjustable wedge block, 8 held in any given position of adjustment by a 40 pair of screws 9, such wedge blocks being also well known.

The blade 4 or 4-5, may be adjusted longitudinally by turning the finger wheel 10 keyed rotatably at 11 in the projection 12 which is part of the wedge block, there being a sliding block 13 threaded upon the 50 screw 14, the block having an upper pin 15 passing through the slot 7 of the iron 4 and through a registering hole in the breaker 5. Since the breaker and the bit are held firmly together by the screw 6 the 55 adjusting movements of the block 13 and

pin 15 move both blades. This method of adjusting the bit is also well known.

Between the sides 17 of the stock a fulcruming cross rod 18 is secured as by riveting. The lever 20 has its lower or front 60 end pressing upon the breaker 5 (or in case of a single blade it would impinge such blade) while its rear end portion is provided with a threaded hole accommodating the screw 23 having the finger wheel 24. 65 A seat is provided in the lever 20 at 25 for engaging the fulcrum rod 18. It is also old to provide such a fulcrum rod, lever and screw for binding the blade firmly at spaced-apart points upon a wedge block as 70 8 or other slanting surface.

Heretofore the binding screw as 23 has been provided with either a rounded or a substantially sharp point. According to such older construction when the binding 75 screw is brought down upon the blade by a threading action the frictional movement of the end of the screw relative to the blade tends to move the blade and the lever as 20 laterally with respect to each other. That 80 is to say, as viewed in Fig. 1, the end of the screw moving in the clockwise direction would tend to creep toward the lower side of the plane forcing the blade toward the upper side. When the end of the screw is 85 rounded this creeping and dislocating movement is quite pronounced, and it results in throwing the cutting edge of the bit out of its true position. Such creeping or blade-shifting action has been overcome to a con- 90 siderable extent in instances where the end of the screw as 23 is made sharp or conically pointed; but a serious objection exists in such construction in that the sharp point causes indentations in the blade and when 95 it is desired to reset the blade the sharp point is very apt to find its way into some old indentation and move the blade out of position while being tightened.

In this connection it is also pointed out 100 that when a screw as 23 is tightened it naturally inclines with respect to the plane of the blade owing to the movement of the upper end of the lever 20 in a direction away from the blade, and when the end of the screw im- 105 pinges the blade the tendency and effect of the end of the screw is also to creep upward upon the blade, springing the screw and putting its threads under undesirable distortion strains, and, where a good grip upon the 110

blade is had by the sharp point, moving the blade upward and carrying the cutting edge out of its desired position.

Another important objection to the older construction in which the end of the screw directly impinges the blade arises from the fact that the holding pressure upon the blade is applied at only a very small point or area and the holding force is therefore necessarily limited. Furthermore there is usually, if not almost invariably, an opening below such small area of contact, as the guideway for the block 13, whereby the pressure of such screw springs the blade and places parts of it under undesirable strains.

From the foregoing references to the older practice it will be clear that according to such practice the holding action upon the iron or bit is limited in quantity and depends to a considerable extent upon spring action developed in the screw or blade, and that the application of force is not direct.

Such want of a proper holding of the blade is important to some extent in practice when the plane is used on straight-grained wood since the blade may be forced back gradually; but it is particularly important in cases where the cutting edge of the blade at one side strikes a knot or other harder material, when that part of the cutting edge is sharply forced back, throwing the blade awry and necessitating its resetting before further use. Such action is possible because the stock sides as 17 are always materially spaced from the adjacent edges of the blade to provide for swinging movements of the blade to compensate for grinding on a line not at right angles to the side edges of the blade.

In order to overcome these and similar objections I provide an intermediate normally non-rotative element between the clamping member and the face surface of the blade toward which the clamping member moves,

such intermediate member communicating the pressure to the blade.

A simple and advantageous form of construction to this end comprises a head 26 at the end of the screw 23, the head or button being preferably flat and disc-like, of materially large diameter, and hollowed out at the bottom so as to provide an annular contacting surface for engaging the blade, the head 26 being swiveled at 27 upon the end of the screw 23 whereby the screw 23 may not only turn relative to the head 26 but may rock somewhat relative thereto, all whereby the force of the screw may be applied centrally of the head 26 and communicated through the head over a relatively large surface of the blade, the friction between the head 26 and the blade normally holding the head against rotative movement while the screw is being turned. The blade is not only thus very tightly held but the tendency to move during the tightening operation is overcome.

I prefer also to form the lever 20, as with a bend at 28, whereby the end portion 22 will overlie the blade in substantially parallel relation thereto whereby the screw 23 will be directed at right angles to the plane of the blade.

I contemplate as being within the scope of these improvements various modifications of and departures from what is specifically herein illustrated and described, as indicated by the appended claim.

I claim:

The combination of a stock and a diagonally-disposed blade in a carpenter's hand plane of the character described, and means for holding the blade including a fulcrumed lever and a clamping screw therein directed toward a face surface of the blade, and a blade-engaging head of materially great area swiveled upon the end of said screw.

SANFOKD S. VAUGHAN.
